UNITED STATES PATENT OFFICE.

CLARENCE E. REED, OF WICHITA, KANSAS.

EARTH-BOARING DRILL.

Application filed March 1, 1927. Serial No. 171,832.

The invention has for one object to provide means of rugged construction for the ready and expeditious assembling of the conical roller cutters with their spindle, apart from the drill head, so that these parts can be inserted into connection with a one piece drill head as units, and when the units are secured in place the roller cutters as a consequence of this act will be locked on their spindles and held against displacement axially thereof so that the full gauge of the hole will be cut at the outset of the cutting operation.

Other objects of the invention will appear from the following description.

15 In the accompanying drawings

Figure 1 is a view of a one piece bit head partly in section and partly in elevation with the cutters mounted thereon, one cutter being in outline only (without showing the teeth) and the other cutter in section.

Fig. 2 is a bottom plan view of the bit head with the cutters and their spindles removed.

Fig. 3 is a plan view of spindle and its shank.

Fig. 4 is a face view of the spindle, with the position of the locking pin indicated by the dotted circle.

Fig. 5 is a view of the spindle detached.

30 Fig. 6 is a sectional view through spindle along the radial plane in which the locking pin is located.

Fig. 7 is a face view of the base of the roller cutter, with only a few of the teeth shown.

Fig. 8 is a view of the locking pin detached.

40 Figs. 9, 10, 10^a, 11, 12, 13, 14 and 15 are views of a different embodiment of the invention.

In these drawings 1 is the one piece bit head having an inverted V-shaped recess 2 at its lower end, in which the conical roller cutters 3 are juxtaposed on opposite sides of the vertical axis, and are adapted to cut the whole area at the bottom of the hole.

The spindle 5^x is of generally cylindrical form, but has steps or shoulders 5^a. It is formed in one piece with its shank 6^x and 50 with the base flange 11^x adapted to fit the

seat recess 12^x in the inclined side wall of the inverted V shaped recess of the head. The base flange may have an enlargement 23 with flat surfaces to fit a supplemental seat recess in the head.

55 The spindle is provided with segmental wings 8^x, 9^x with gates 10^x between forming a part of a bayonet joint connection between the spindle and the conical roller cutter. Another part of this bayonet joint connection is a locking pin. This has cylindrical ends or heads 24, 24^a connected by a reduced neck portion 25. It is adapted to be seated in a recess 26 in the base of the spindle and in a partial extension 28 of said recess formed in the side of the spindle.

60 The upper head 24 of the locking pin when in place fits in the recess 26 while the other head 24^a fits in the partial or laterally open recess or extension 28 and projects therefrom laterally from the side of the spindle to an extent substantially equal to the extent that the wings 8^x and 9^x project from the side of the spindle and said pin is intended to be seated in the gate intermediate of the said wings and in line with the gate between the wings or flanges. When seated the head 70

75 24^a of the locking piece is circumferentially in line with the wings, while its neck is circumferentially in line with the space or groove 29 between the wing 8^x or 9^x and the face of the base 11^x of the spindle.

80 Fig. 4 is a face view of the spindle, with the position of the locking pin indicated by the dotted circle.

85 Fig. 5 is a view of the spindle detached.

Fig. 6 is a sectional view through spindle along the radial plane in which the locking pin is located.

90 Fig. 7 is a face view of the base of the roller cutter, with only a few of the teeth shown.

Fig. 8 is a view of the locking pin detached.

95 Figs. 9, 10, 10^a, 11, 12, 13, 14 and 15 are views of a different embodiment of the invention.

In these drawings 1 is the one piece bit head having an inverted V-shaped recess 2 at its lower end, in which the conical roller cutters 3 are juxtaposed on opposite sides of the vertical axis, and are adapted to cut the whole area at the bottom of the hole.

The spindle 5^x is of generally cylindrical form, but has steps or shoulders 5^a. It is formed in one piece with its shank 6^x and 100 with the base flange 11^x adapted to fit the

ing flanges come in line with the space or groove 29 at the spindle. The roller cutter is then turned to make its flanges engage behind the wings and to bring one of its 5 gates into line with the recess or seat 26—28 in the spindle which is to receive the locking pin. The locking pin is then inserted and its head 24^a passes through the gate in the flange of the roller cutter. The 10 parts as thus assembled are inserted in the bit head with the shank 6^x of the spindle in the socket 7^x of said head. The base flange of the spindle is thereby seated against the ceiling of the seat recess 12^x of the bit 15 head and by this act the locking pin 24—24^a is held in the position just described because its head 24 finds a bearing against said ceiling, and it will be held in proper position by bearing at one end against said ceiling and at its other end by resting upon the bottom of the extension 28 of the recess in the spindle. The roller cutter when placed as above described will be retained on the spindle and in exactly the prescribed position to cut the desired gauge of the hole.

When the gates in the roller cutter register with the wings 8^x, 9^x of the bayonet joint connection then the head 24^a of the locking pin will prevent disengagement of the roller 30 cutter because said head 24^a will engage the overhanging flange of the cutter lying between its gates. There being but two gates on the cutter forming elements of one part of the bayonet joint, and there being two 35 complementary wings and a third element, i. e. the locking piece forming the elements of the other part of the bayonet joint, registry of the gates of the one part cannot take place with all of the elements of the other 40 part at the same time, hence the roller cutter will be retained in proper working position on the spindle so long as the cutter organization is mounted in proper position in the bit head.

45 To take a cutter from the head it is necessary to remove the unit composed of the cutter, the spindle with its base and shank, from the bit head, in order that access may be had to the locking piece, for its removal. 50 To accomplish this removal of the locking piece after the unit is removed from the head, the roller cutter is turned so that one of its gates will register with the locking piece which is then withdrawn. The roller cutter is then turned until its gates register 55 with the wings 8^x, 9^x, whereupon it may be withdrawn.

It will be observed that I provide a rugged 60 construction for holding the roller cutter on the spindle, the interlocking parts being comparatively massive, not liable to "freeze" in place, and registration of the parts and their interlocking being accomplished quickly and by ordinary labor.

65 The insertion of a unit into the head takes

place without crossing the line of the vertical axis of the drill head and the construction described permits the assembly of the roller cutters into a one piece bit head having a recess in its lower end despite the fact 70 that the conical roller cutters occupy the recess substantially completely from side to side of the recess, to cut the entire area at the bottom of the hole, and despite the fact that the roller cutters are mounted on spindles which project downwardly and inwardly from the side walls of said recess towards the vertical axis of the drill head.

75 It will be noted further that the locking member is not subjected to thrust or wear 80 excepting the comparatively slight degree resulting from preventing axial movement of the roller cutter on the spindle and as to this its action is merely supplementary to the interlocking flanges of the bayonet joint and 85 only at intervals i. e. when the gates and flanges register. At all other times during the revolution of the roller cutter the maintenance of the cutter in its prescribed position on the spindle will be taken by the 90 flanges.

The spindle 5^x, its base 11^x and its shank 6^x are formed in one piece.

The locking pin is introduced into the spindle by moving it parallel with the axis 95 thereof from its outer end, and from the top side or outer face of the base.

The spindle may be held in the head by any suitable means such as shown at 15^x.

In Figures 9, 10, 10^a, 11, 12, 13, 14 and 15, I show a form of tool in which two frusto-conical sections of the roller cutters are mounted on the same spindle. Figs. 9 and 11 are partly in section on two different planes and are diagrammatic in character. The spindle 5^y is hollow to receive the shank 3^y of the small conical section of the roller cutter. This shank is provided with a flange 3^f and a gate 3^g to cooperate with wings on the interior of the spindle. The 100 wings may be provided by pieces like that shown in Figs. 8, 13 and 14, which are inserted into the spindle through openings 3^h in the base flange. The piece which is inserted last may be said to be the locking 105 piece of the first described construction as it performs the final act of locking the roller cutter to the spindle. These wings or locking pieces are inserted from the back of the base flange and they will be held in place 110 in their sockets by the wall of the head when the unit is mounted in said head. They abut at their ends upon the bottoms 3ⁱ of the sockets or recesses in the spindle. The wings 115 or locking pieces need no special means for holding them in place, as they will be confined, like the locking piece previously described between the wall of the bit head and the abutment 3ⁱ, and will be inaccessible except by taking the unit from the head.

The other section 3¹ of the rotary cutter will be mounted on the outer side of the spindle and it will be held in place by the small conical section.

- 5 It will be seen from the above that the wing or wings of the spindle may be integral therewith or said wing or wings if more than one wing is used in addition to the locking piece, may be provided by inserting pieces 10 similar to the locking piece, and this statement applies whether the wings and locking piece are inside of the spindle, as shown in Figs. 9, 10 and 11 or outside of said spindle as shown in the first described form.
- 15 For convenience of terminology it will be understood that where the words "on the spindle" are used in the claims they mean either that the roller is mounted on the outside of the spindle or on the inner side there- 20 of, both forms being illustrated.

The locking means for holding the spindle shank in the bit head is claimed in another case.

The specific form of the invention shown 25 in Figs. 9 to 15 forms the subject of a divisional application.

I claim:

1. In an earth boring drill the combination of a bit head, a roller cutter, a spindle 30 with means for detachably holding it in the bit head, and a bayonet joint connection between the roller cutter and the spindle, including complementary flanges and gates on the spindle and roller cutter and a locking 35 member removably mounted on the spindle and obstructing one of the gates to hold the roller to the spindle when the gates and flanges register, said locking piece being held in place by the wall of the head, substan- 40 tially as described.

2. In an earth boring drill the combination of a bit head, a spindle with means for detachably holding it to the bit head, and having a recess to receive a locking pin, a 45 roller cutter, said roller cutter and spindle having a bayonet joint connection between them, and a locking pin seated in the recess on the spindle, obstructing a gateway of the bayonet joint connection and preventing dis- 50 engagement of the parts of said bayonet joint connection, said locking pin being in- accessible for removal except by removing the spindle with its attached roller cutter from the bit head, substantially as described.

- 55 3. In combination in an earth boring drill, a bit head, a spindle having a base portion seated against the head, and having a recess, a roller cutter, said roller cutter and spindle having a bayonet joint connection 60 between them, and a locking piece seated in the recess of the base of the spindle for preventing disconnection of the bayonet joint, said locking piece being retained in position by the wall of the head covering 65 said recess and removable only for the

detachment of the roller cutter when the spindle and roller cutter are removed from the head, substantially as described.

4. In combination in an earth boring 70 drill, a bit head having a substantially inverted V-shaped recess in its lower end, with a seat recess in the inclined wall thereof, a spindle having a base located in said seat recess and sustaining thrust by contact with the wall of said seat recess, a roller cutter, 75 said roller cutter and spindle having flanges to interengage, and a locking member seated removably in the base of the spindle and engaging the flange of the roller cutter to hold it on the spindle, said locking member being retained by the wall of the head and accessible for placing or removing only when the spindle is detached from the head, substantially as described.

5. In an earth boring drill, the combination of a bit head, a roller cutter, a spindle with means for detachably holding it in the head, said spindle and roller cutter having a connection between them to retain the roller cutter in position when the cutter bears one 90 relation to the spindle in a circumferential direction, and to permit removal of the roller cutter in another circumferential position, and a locking member to prevent removal of the roller in the last named position, said locking member being retained seated in the spindle by the wall of the head, and removable from its effective position only when the spindle is removed from the head, substantially as described.

6. In combination in an earth boring 95 drill, the combination of a bit head, a spindle removably mounted thereon, a roller cutter, a connection between the roller cutter and the spindle comprising interengaging flanges, which are disengageable when the roller is in one position rotatively on said spindle, and a locking piece composed of two head portions with a reduced neck portion between, said locking piece being seated removably in the spindle with its lower head portion in line circumferentially with the flange on the spindle and its neck portion in line with the flange on the roller, said locking piece holding the roller cutter on the spindle when the flanges disengage, and being accessible for removal only when the spindle is removed from the head.

7. In combination in an earth boring 110 drill, a bit head, a spindle extending inwardly and downwardly towards the vertical axis of the head and having a shank extending into a socket within the head and at an angle to the axis of the spindle, a connection between the spindle and roller comprising interengaging flanges and a locking pin inserted into the spindle from its outer end and retaining the roller on the spindle when the flanges are in disengaged position, substantially as described.

8. In combination in an earth boring drill, a bit head, a spindle projecting from the head, a roller cutter mounted on the spindle, flanges on the spindle and roller interengaging when the roller occupies a certain position circumferentially of the spindle and disengaging in another circumferential position of the roller to permit removal of the roller by a movement in the direction of the roller axis, and a locking pin inserted into a recess in the spindle parallel with the axis of the spindle and from the outer end of the spindle and preventing said removal of the roller so long as said locking pin is in place, substantially as described.
9. In combination in an earth boring apparatus, a one piece bit head, a pair of opposed cutters at the lower end thereof to cut the entire area at the bottom of the hole, said cutters being juxtaposed on opposite sides of the vertical axis of the drill, and a one piece spindle and shank on which spindle one of the cutters is assembled to be inserted with said spindle and its shank into the head as one unit and in close proximity to the previously assembled roller cutter, substantially as described.
10. In combination, a one piece head, a spindle and shank in one piece, a roller cutter mounted on the spindle, a flanged and gate connection between the roller and spindle, and a locking piece inserted into a gate of the spindle after the roller cutter is mounted thereon to obstruct said gate against removal of the cutter, substantially as described.
11. In combination in an earth boring drill, a bit head, a spindle carried thereby, a roller cutter on the spindle, said spindle and roller cutter having a connection between them comprising interengaging parts, which hold the roller rotatively on the spindle when in one circumferential position and permit the roller to be removed axially when in another circumferential position, and a locking piece insertible to and removable from the spindle for retaining the roller on the spindle in the last mentioned position, said connection and locking piece permitting free rotation of the roller on the spindle.
12. An earth boring apparatus according to claim 11 in which the locking piece is inserted in a direction from the outer end of the spindle towards the roller cutter.
13. A roller cutter unit for earth boring drills comprising a spindle and a roller cutter, having complementary projections and gate spaces, and a locking piece insertible into and removable from a seat on the spindle through the gate space of the roller into the gate space of the spindle, said projections and locking piece holding the roller against axial movement while allowing the

same to rotate on the spindle, substantially as described.

14. A roller cutter unit according to claim 13 in which the spindle is provided with a shank extending at an angle thereto for insertion into the bit head, and a base surface to bear against the bit head, said base surface being substantially at right angles to the spindle, said locking piece being inserted from the outer end of the spindle, substantially as described.

15. An earth boring drill according to claim 11 having a base flange at the outer end of the spindle bearing on the bit head, the locking piece being inserted through said base flange into the spindle.

16. A rotary earth boring drill according to claim 11 in which a base flange is at the outer end of the spindle bearing upon the bit head and a shank extends at an inclination to said flange into the said head, the locking piece being inserted through an opening at one side of the shank, substantially as described.

17. An earth boring drill having a bit head with a spindle thereon, a conical roller cutter covering the end of the spindle, said spindle and roller cutter having complementary projections and gate spaces permitting placing or removal of the roller in one circumferential position and preventing removal of the roller from the spindle in another circumferential position of the roller, and a locking piece insertible from the outer end of the spindle through the gate space of the roller cutter and into the gate space of the spindle to prevent removal of the roller when the gates register with the projections, said projections and locking piece holding the conical roller cutter on the spindle against axial movement while allowing free rotation, substantially as described.

18. An earth boring drill according to claim 17 in which the locking member has a laterally extending head portion in the spindle gate space, and a shank portion lying to one side of the path described by the projection on the roller cutter.

19. In combination in an earth boring drill, a bit head, a spindle thereon, a roller cutter mounted on the spindle, said roller having at least one gateway and a projecting portion, and said spindle having at least two projections severally complementary to the gateway, at least one of said projections being insertible into and removable from operative relation to said spindle, said spindle being attached to the roller cutter by moving it axially relatively into the bore of the roller to pass its projection through the gateway, whereupon the roller is turned to present its gateway to the location of the other projection which is then inserted through said gateway, substantially as described.

20. In combination in an earth boring apparatus, a one piece bit head having a bore, and a recess in the lower wall, a pair of opposed cutters at the lower end of the head
5 to cut the entire area at the bottom of the hole, said cutters being juxtaposed on opposite sides of the vertical axis of the drill, and a one piece spindle having a base and a shank, on which spindle one of the cutters is assembled to be inserted with said spindle, 10 the shank in the bore in the head and the base in the recess in the head.

In testimony whereof, I affix my signature.

CLARENCE E. REED.
